UNITED STATES PATENT OFFICE.

LOUIS A. STRAUBEL, OF GREEN BAY, WISCONSIN.

PAPER-FOLDING MACHINE.

Application filed September 12, 1924. Serial No. 737,860.

To all whom it may concern:

Be it known that I, LOUIS A. STRAUBEL, a citizen of the United States, and resident of Green Bay, in the county of Brown and State of Wisconsin, have invented certain new and useful Improvements in Paper-Folding Machines; and I do hereby declare that the following is a full, clear, and exact description thereof.

10 This invention relates to interfolding machines and is particularly directed to double fold interfolding machines which are adapted to produce packages of interfolded sheets of paper.

15 The primary purpose of this invention is to produce an interfolding machine which will hold the paper at each fold immediately after the fold has been produced, and which will hold the central portion of the 20 folded paper to prevent bulging or unfolding, thus adapting the machine to the handling of even the thinnest kinds of paper such as toilet paper for instance.

25 In general this invention is an improvement over that disclosed in my United States Patent Number 1,423,276 of July 18, 1922, for paper folding machines and has the same general objects as those set forth in the above noted patent, in addition to 30 the specific objects enumerated above.

35 Further objects are to provide an interfolding machine in which the several holding or presser flaps and tucking blades are operated in a regular manner by extremely simple mechanism having very few parts, and so formed that all of the parts are rugged and reliable and are not likely to get out of order.

40 Further objects are to provide an improved form of holder plates for the folded paper which are so constructed that the paper is securely held against shifting, even at the time during which the fold is made, thus insuring the production of a package 45 of uniform width although formed of interfolded separate sheets.

50 Further objects are to provide a machine for producing interfolded sheets of this paper in which a combination of long and short presser flaps is employed, the former to hold the folded portion of the paper immediately after tucking and the latter to hold an intermediate portion of the folded paper to prevent disengagement of the last 55 or loose sheet, and to thus keep such sheet

clear of the tucking blades under all conditions.

An embodiment of the invention is shown in the accompanying drawings, in which:— 60 Figure 1 is a fragmentary view of the cams and oscillating mechanism therefor, and of the cam followers showing in dotted lines the position of the feed rollers.

Figure 2 is an elevational view looking in at the front of the machine, said view 65 showing certain of the parts in section for clearness of illustration.

Figure 3 is a view of the ends of the holding means for the package of folded paper. 70

Figure 4 is a diagrammatic view showing the folding mechanism in one of its extreme positions.

Figure 5 is a view corresponding to Figure 4 showing the folding mechanism in its 75 other extreme position.

Figure 6 is a fragmentary edge view of the structure shown in Figure 3.

The machine is of substantially the same form as that disclosed in my above noted 80 patent and the details of the machine which are similar to the patented structure need not therefore be developed.

In interfolding machines forming part of this invention, a crank shaft 1 is provided and is driven through the medium of a gear 2 connected with the feed and other 85 portions of the machine and correctly timed therewith.

This crank shaft is provided with a crank 90 at each end, as indicated at 3 and 4 in Figure 1, and such cranks are connected by means of links 5 and 6 with bell cranks 7 and 8. These bell cranks are rigidly secured to shafts 9 and 10, such shafts project through the body of the machine and preferably the cranks being positioned on opposite ends of the machine, as shown in Figure 2. These shafts 9 and 10 carry, respectively, cam members 11—12 and 13— 140 14 which are arranged in pairs at opposite ends of the machine, as may be seen from Figure 2, and in spaced relation to each other. These cam members are each provided with cutout ends 15 and with substantially circular faces 16 concentric with the axis of the respective shafts, as shown in Figure 1.

A plurality of relatively small rock arms 17 and 18, and 19 and 20 are rigidly 185 190 195 200 secured to the cam members 11—12 and 13—14, respectively, and are arranged to hold the paper in the desired position.

cured to shafts 21 and 22, and 23 and 24, and are provided with rollers adapted to contact with the cams 11-12 and 13-14, respectively. It is preferable to provide these cam followers in pairs at opposite ends of the machine, as shown in Figure 2, and to accordingly mount the appropriate cams in pairs at such ends. This avoids needless interference and complicated construction. The shaft 1 extends completely across the machine and insures the correct relative timing of the cams.

Upon reference to Figure 4, it will be seen that the shafts 21 and 24 are provided with flat faces to which relatively long presser arms or flaps 25 and 26 are respectively secured. These presser arms terminate in spaced presser feet 27 and 28 which are adapted to engage an intermediate portion of the folded paper packed, as shown in Figures 4 and 5. The shafts 22 and 23 carry relatively short presser flaps 29 and 30 which are preferably provided with cutout portions 29' and 30' respectively at regular intervals adapted to receive the projecting tongues 31 and 32 of the package holding means. For example, the tongues 31 may be formed integrally with the table 33 and a second plate 34 may be spaced above the plate or table 33 and formed integrally with the tongues 32. The shapes of the tongues are clearly shown in Figure 3, which details an end of the upper plate 34. It is also preferable, as shown in Figures 4, and 5, to form flat faces or cut away portions 35 upon the shafts 22 and 23 to permit the close approach of the long presser arms 25 and 26.

The shafts 9 and 10 carry the tucker arms 37 and 38, respectively, which terminate in the tucker blades 39 and 39. It is to be noted that the oncoming paper sheet is fed downwardly by means of the rollers 40 which are of the type disclosed in my above noted patent and the lower ends of these separate sheets of paper are received in the last fold of the preceding sheet, as clearly shown in Figure 4.

In describing the operation of the machine, assume that the parts are in the position illustrated in Figure 4. It will be seen that the tucker blade 39 has just passed downwardly into the previously partly folded sheet, and that the short presser flap 29 has rocked outwardly a slight distance while the long presser flap 25 has rocked outwardly a material distance. It is to be noted that the short presser flaps 29 and 30 are beveled on their inner faces, and that the tucker blades readily tuck the paper past these beveled faces. After the machine has arrived at the stage of operation illustrated in Figure 4, the tucker blade 39 rises and withdraws from the fold just formed. The short presser flap 29 immediately presses

this fold inwardly and the long presser flap 25 moves inwardly an instant later and presses an intermediate portion of the fold pack. Thereafter the presser flaps 20 and 26 move outwardly and the tucking blade 38 moves upwardly into the position shown in Figure 5, thus tucking the new sheet behind the short presser flap 30, as illustrated in such figure. When this tucking blade moves downwardly the short flap 30 immediately presses the paper adjacent the fold before the tucking blade has moved out of the range of the long presser flap 26. Thereafter, the long presser flap moves inwardly and presses the central portion of the package of paper inwardly.

This alternate cycle of operations is repeated indefinitely or until a suitable quantity of paper has been folded.

It is to be particularly noted that by providing these movable presser flaps, namely, the short presser flaps engaging the paper adjacent the fold, and the long presser flaps engaging the paper approximately centrally of the package that a very thin flimsy type of paper may be most readily handled by the machine, and that the folding may be most accurately done without danger of the loose or last end of the folded paper inadvertently becoming entangled or cut by other portions of the mechanism.

It will also be seen that the holding means 33 and 34 extend through the short presser flaps 29 and 30 and maintain the interfolded package of paper in a uniform condition and of a uniform width of package.

It is to be particularly noted that the holding means, or plates, 33 and 34 keep the interfolded stock from contacting with the rock shafts 22 and 23. Further, the projecting tongues extending through the short presser flaps prevent chewing or catching of the paper by such short presser flaps. As shown particularly in Figure 6, the tongues of the holding plates are preferably corrugated to secure a firmer hold upon the outermost portion of the interfolded stock and to thus aid in preventing the outermost folds from springing out when temporarily released by one or the other of the short presser flaps.

It will thus be seen that an interfolding machine has been provided which will most easily handle very thin tissue paper of a flimsy and fragile nature, which will accurately fold such paper in a rapid and efficacious manner, and which consists of a very small number of rugged and strong parts not likely to get out of order.

Although the invention has been described in considerable detail, it is to be understood that the invention may be variously embodied and is, therefore, to be limited only as claimed.

I claim:

1. In an interfolding machine, the combination of means for feeding sheets, a pair of spaced presser flaps adapted to engage and press the sheets adjacent the folded portion thereof, a pair of tucker blades adapted to tuck the sheets immediately to the rear of the presser flaps, and a second pair of presser flaps adapted to press the interfolded sheets against the previously folded stock at approximately the central portion.
2. In an interfolding machine, the combination of means for feeding separate sheets of paper in a regular sequence, a pair of tucker blades adapted to engage the paper in opposite directions, a pair of short presser flaps adapted to receive the portion of the paper engaged by the tucker blades and to cooperate with said blades to form folds, and a pair of longer presser flaps adapted to alternately engage the folded paper intermediate the folds to press such paper against the folded stock.
3. In an interfolding machine, the combination of a pair of rock shafts, a pair of cams carried by each rock shaft, a pair of cam followers for each pair of cams, a pair of presser flaps rigidly connected with each pair of cam followers and consisting of a short presser flap and a long presser flap, means for successively feeding separate sheets of paper, and a pair of tucker blades rigidly secured to said rocker shafts and adapted to engage the paper sheets from opposite sides and to tuck them behind said short presser flaps, said long presser flaps engaging the folded paper intermediate the folds.
4. In an interfolding machine, the combination of a pair of rock shafts, a pair of cams carried by each rock shaft, a pair of cam followers for each pair of cams, a pair of presser flaps rigidly connected with each pair of cam followers and consisting of a short presser flap and a long presser flap, means for successively feeding separate sheets of paper, and a pair of tucker blades rigidly secured to said rock shafts and adapted to engage the paper sheets from opposite sides and to tuck them behind said short presser flaps, said long presser flaps engaging the folded paper intermediate the folds.
5. In an interfolding machine, the combination of means for feeding sheets, a pair of spaced presser flaps adapted to engage and press the sheets adjacent the folded portion thereof, said presser flaps having a series of apertures adjacent their outer edges, a pair of tucker blades adapted to tuck the sheets immediately to the rear of the presser flaps, a second pair of presser flaps adapted to press the interfolded sheets against the previously folded stock at approximately the central portion, and a pair of spaced holding plates adapted to receive and hold the interfolded sheets between them, said plates having tongues extending through the apertures in the first mentioned presser flaps.
6. In an interfolding machine, the combination of means for feeding sheets, a pair of spaced presser flaps adapted to engage and press the sheets adjacent the folded portion thereof, said presser flaps having a series of apertures adjacent their outer edges, a pair of tucker blades adapted to tuck the sheets immediately to the rear of the presser flaps, a second pair of presser flaps adapted to press the interfolded sheet against the previously folded stock at approximately the central portion, and a pair of spaced holding plates adapted to receive and hold the interfolded sheets between them, said plates having corrugated tongues extending through the apertures in the first mentioned presser flaps.

In testimony that I claim the foregoing I have hereunto set my hand at Green Bay, 95 in the county of Brown and State of Wisconsin.

LOUIS A. STRAUBEL.
